UNITED STATES PATENT OFFICE

FRANK H. DERBY, OF ERIE, PENNSYLVANIA, ASSIGNOR TO ERIE FOUNDRY COMPANY,
OF ERIE, PENNSYLVANIA, A CORPORATION OF PENNSYLVANIA

HAMMER

Application filed May 27, 1929. Serial No. 366,245.

Power hammers are usually provided with some means of adjusting the hammer carrying guides with relation to the anvil. The present invention is designed to improve this adjustment. In carrying out the invention wedges are used for adjusting the parts relatively to each other in two directions and improved means are provided for locking the wedges in adjustment and also for locking the wedges with the parts on which they are adjusted so as to permit of a slight free movement between the uprights of the hammer and the base. Features and details of the invention will appear from the specification and claims.

A preferred embodiment of the invention is illustrated in the accompanying drawings as follows:—

Fig. 1 shows a front elevation of the hammer.
Fig. 2 a side view of the same.
Fig. 3 a top view of the base.
Fig. 4 a section on the lines 4—4 in Figs. 2 and 3.
Fig. 5 a section on the lines 5—5 in Figs. 1 and 3.

Fig. 6 a perspective view of the laterally extending wedge.

Fig. 7 a perspective view of the forward and back extending wedge.

Fig. 8 an enlarged view of a wedge locking plate.

Fig. 9 a perspective view of the same plate. 1 marks the hammer base carrying the anvil portion, 2 the uprights on the base, and 3 the hammer head. The uprights are provided with guides 4 in which operate a hammer 5. The hammer is carried by a piston rod 5a extending to a piston (not shown) in a cylinder 6. The uprights are tied together by rods 7 and 8 at the bottom and top respectively. Dies 9 and 10 are arranged on the anvil and hammer head. The uprights are yieldingly held on the base by means of bolts 11 which operate through springs 12 on the uprights in clamping them on the base. Wedges 13 extend forward and back between opposing shoulders 14 and 15 on the base and upright respectively. The wedge has a tongue and groove connection 16 with the shoulder 15

so that the wedge is locked to move with the upright as the upright is lifted slightly with the blow.

The ends of the wedge 13 are provided with slots 17 through which extend bolts 18. The wedge is provided with serrations 19 and a clamping plate 20 is provided with a perforation 21 through which the bolt 18 extends and is provided with serrations 22 corresponding with the serrations 19 which serrations when the plate 20 is clamped against the wedge by means of the bolt 18 lock the wedge definitely in adjustment.

The axis 23 of the bolt is slightly off-set from the peak 24 of the serrations 22. By reason of this arrangement the plate may be reversed on the bolt and thus give a finer adjustment than the full width of the serrations.

Lips 25 extend downwardly on the front and back sides of the uprights and form laterally extending shoulders, one shoulder engaging the edge 26 of the base and the other lip being engaged by a wedge 27 which is arranged in a seat 28 on the edge of the base. The wedge 27 is locked with the base by a tongue and groove 29. The wedge is provided with a slot 30 and serrations 31. A bolt 32 extends through the slot and a plate 33 corresponding to the plate 20, the bolt clamping the plate 33 against the serrations locking the wedge in adjustment in the same manner as does the plate 20 on the wedge 13.

The wedges 13 adjust the uprights relatively to the base sidewise and the wedges 27 adjust the uprights forward and back, ordinarily the lip and edge 26 providing the proper adjustment but, if desired, this may be varied by shimming between the edge 26 and the lip 25. The wedges 13 and 27 cross each other, being arranged on different planes and it will be noted that the tongue and groove connection of the wedges 13 is with the upright and that the adjusting bolts 18 are carried by the upright. In the same manner, the wedges 27 have a tongue and groove connection 29 with the base and adjusting bolts 32 extend into the base, and project through slots 30. The wedges have serrations 31 which are engaged by a plate 33 similar

to the plate 22. The plate 33 is clamped by a bolt 32 and the adjustment is secured in the same manner as with the wedges 13.

What I claim as new is:—

- 5 1. In a hammer, the combination of a base; guide uprights on the base; opposing wedge shoulders on the base and an upright; a wedge between the shoulders, said wedge having a tongue and groove connection with one 70
10 of the shoulders; and locking means on the shoulder having the tongue and groove connection for the wedge locking the wedge in adjustment; the peaks of the serrations being out of register with the axis of the bolt.
- 15 2. In a hammer, the combination of a base; guide uprights on the base; opposing wedge shoulders on the base and an upright, said shoulders extending crosswise of each other, one laterally and the other forward and back; a wedge between the laterally extending shoulders; and a wedge between the forward and back extending shoulders.
- 20 3. In a hammer, the combination of a base; guide uprights on the base; opposing wedge shoulders on the base and an upright, said shoulders extending crosswise of each 80
25 other, one laterally and the other forward and back; a wedge between the laterally extending shoulders; and a wedge between the forward and back extending shoulders, said wedges being in different planes and crossing 90 each other.
- 30 4. In a hammer, the combination of a base; guide uprights on the base; opposing wedge shoulders on the base and an upright, said shoulders extending crosswise of each 95
35 other, one laterally and the other forward and back; a wedge between the laterally extending shoulders; and a wedge between the forward and back extending shoulders, one of said wedges having a tongue and groove 100
40 connection with the upright and the other wedge a tongue and groove connection with the base.
- 45 5. In a hammer, the combination of a base; guide uprights on the base; opposing wedge shoulders on the base and an upright, said shoulders extending laterally and forward and back; a wedge between the laterally extending shoulders; a wedge between the forward and back extending shoulders, one of said wedges having a tongue and groove 105
50 connection with the upright and the other wedge a tongue and groove connection with the base; and means locking the wedges in adjustment.
- 55 6. In a hammer, the combination of a base; guide uprights on the base; opposing wedge shoulders on the base and an upright, said shoulders extending crosswise of each other, one laterally and the other forward and back; wedges between the laterally extending shoulders; and wedges between the forward and back extending shoulders.
- 60 7. In a hammer, the combination of a base; guide uprights on the base; opposing wedge shoulders between the base and each upright, said shoulders at each upright extending crosswise of each other, one laterally and the other forward and back; wedges between the laterally extending shoulders; and wedges between the forward and back extending shoulders.
- 65 8. In a hammer, the combination of a base; guide uprights on the base; opposing wedge shoulders between the base and each upright, said shoulders at each upright extending crosswise of each other, one laterally and the other forward and back; wedges be- 115

tween the laterally extending shoulders; wedges between the forward and back extending shoulders, each of said wedges having a tongue and groove connection with a shoulder; and locking means for each wedge locking the wedge with the shoulder having the tongue and groove connection.

5 In testimony whereof I have hereunto set my hand.

FRANK H. DERBY.
